UNITED STATES PATENT OFFICE.

JOHN HERRON, OF MARQUETTE, MICHIGAN, ASSIGNOR OF ONE-HALF TO JOHN E. RABY, OF MARQUETTE, MICHIGAN.

RAIL-ANCHOR.

1,208,779.

Specification of Letters Patent. Patented Dec. 19, 1916.

Application filed May 6, 1915. Serial No. 26,294.

To all whom it may concern:

Be it known that I, JOHN HERRON, citizen of the United States, residing at Marquette, in the county of Marquette and State 5 of Michigan, have invented certain new and useful Improvements in Rail-Anchors, of which the following is a specification.

This invention relates to devices for preventing the longitudinal creep of railway 10 rails, the same consisting essentially of a yoke or similar member which is clamped in fixed position on the rail by means of a wedge having one end abutting against one of the ties on which the rail is laid, the 15 tie therefore serving as an abutment to hold the rails against a tendency to creep.

The invention has for its object to provide a simple and efficient device of the kind stated characterized by an improved 20 means for clamping the part which is fixed to the rail, whereby said part is firmly secured to the rail and prevented from getting loose.

The object stated is attained by means of 25 a novel combination and arrangement of parts to be hereinafter described and claimed, reference being had to the accompanying drawing in which—

Figure 1 is a plan view showing the application of the invention; Fig. 2 is a cross section on the line 2—2 of Fig. 1; Fig. 3 is a longitudinal section on the line 3—3 of Fig. 2, and Fig. 4 is a perspective view of a wedge key.

Referring specifically to the drawing, 10 denotes the rail and 11 one of the cross-ties or stringers supporting the same. The rail anchor is a yoke 12, of substantial width. The yoke is located transversely beneath the rail and has jaws 13 and 14, respectively, at its ends to bear on opposite edges of the base of the rail. Below that portion of the jaw 13 which engages the adjacent side of the rail base is a lateral 40 recess 15 to accommodate this side of the rail base while the yoke is raised to engage the jaw 14 over the other side of the rail base. The yoke is then allowed to drop, whereupon the jaws properly engage the sides of the rail base. The jaws overhang the rail base for a short distance from the longitudinal edges of the latter, as indicated at 16, and have shoulders 17 which abut against said edges. The recess 15 of

the jaw 13 is below and back of the shoulder thereof.

The intermediate portion of the yoke 12 between the jaws 13 and 14, lying beneath the rail base, is bowed slightly downward to leave sufficient space between the top of the yoke and the bottom of the rail base to accommodate a key 18. This key is rigid and has a wedge portion 19, and the yoke is slightly resilient, so that when the key is driven in between the rail base and the yoke, the latter is bent or put under tension sufficiently to shorten the distance between the jaws 13 and 14 in a direct line, causing said jaws to grip the top and edges of the rail base firmly and equally on both sides, and thereby preventing the yoke from slipping along the rail.

On the under side of the wedge 19, are ratchet teeth 20, and intermediate the ends of the yoke 12 the latter has a relatively narrow top raised portion or rib which slopes to form an incline 21 corresponding to the width and taper of the wedge and provided with ratchet teeth 22. When the key is in place, the ratchet teeth 20 and 22 interlock, and as they are shaped to lock the key against movement in a direction to withdraw, the key is securely held in place. The wedge portion 19 of the key and the incline 21 engageable by the same run in the direction of the length of the rail and are directly in the center of the rail base, and from the latter the key extends over sidewise as far as the recess 15 in which its outer longitudinal edge seats, said recess being below the plane of the bottom of the rail base when the yoke is in place. That portion of the key which is to one side of the wedge serves to hold the latter in true alignment or at a right angle to the yoke and parallel to the rail. It is therefore impossible for the wedge to be dislodged sidewise, which is important as such displacement would relieve the gripping strain and render the device useless.

The end of the key 18 at the large end of the wedge 19 has a head or enlargement 23 to abut against one side of the tie 11. The device is applied by placing the key against the tie, directly under the rail, after which the yoke 12 is put on the rail, in front of the key, and driven back toward the tie, over the key, until it is tightly

wedged and locked in the manner hereinbefore described.

The location of the wedge 19 and the cooperating incline 21 midway between the ends of the yoke 12 flexes the latter from the center, in view of which the jaws 13 and 14 grip the sides of the rail base with equal force. The yoke also flexes equally throughout its entire width from front to rear as the wedge does not bear on the yoke but on the incline only. It will therefore be evident that the jaws grip the rail base throughout their entire width.

The structure provides a simple and very efficient rail anchor which can be made in different sizes to fit different weights of rail sections. The wedge key is automatically locked, and the greater the pressure thereagainst by its abutment against the tie, the greater will be the grip on the rail.

I claim:

1. A rail anchor comprising a resilient yoke extending transversely beneath the rail and having jaws at its ends engaging opposite sides of the rail base, an incline on top of the yoke intermediate the ends thereof, and a wedge driven between the under side of the rail base and the incline, said incline and the wedge having interlocking parts.
2. A rail anchor comprising a resilient yoke extending transversely beneath the rail and having jaws at its ends engaging opposite sides of the rail base, an incline on top of the yoke intermediate the ends thereof, and a wedge driven between the under side of the rail base and the incline, the contiguous portions of the wedge and the incline having interlocking teeth for locking the wedge against withdrawal.
3. A rail anchor comprising a resilient yoke extending transversely beneath the rail and having jaws at its ends engaging opposite sides of the rail base, an incline on top of the yoke intermediate the ends thereof, a key between the yoke and the under side of the rail base, one side of the key abutting against one of the jaws of the yoke, and the other side having a wedge engageable with the incline, and said wedge and incline having interlocking parts.

4. A rail anchor comprising a resilient yoke extending transversely beneath the rail and having jaws at its ends engaging opposite sides of the rail base, an incline on top of the yoke midway between the ends thereof and extending in the direction of the length of the rail, a key between the yoke and the under side of the rail base, one side of the key having a wedge engageable with the incline, and the other side of the key abutting against one of the jaws of the yoke, said jaw having a recess located below the plane of the underside of the rail base, in which recess the last mentioned side of the key seats.

5. A rail anchor comprising a resilient yoke extending transversely beneath the rail and having jaws at its ends engaging opposite sides of the rail base, and a key between the yoke and the under side of the rail base one side of the key abutting against one of the jaws of the yoke, and the other side having a wedge engaging the yoke midway between its ends for flexing the same, said wedge and yoke having interlocking parts.

6. A rail anchor comprising a resilient yoke extending transversely beneath the rail and having jaws at its ends engaging opposite sides of the rail base, and a key between the yoke and the underside of the rail base, one side of the key having a wedge engaging the yoke midway between its ends for flexing the same, and the other side of the key abutting against one of the jaws of the yoke, said jaw having a recess located below the plane of the under side of the rail base, in which recess the last mentioned side of the key seats.

7. A rail anchor comprising a resilient yoke extending transversely beneath the rail and having jaws at its ends engaging opposite sides of the rail base, a rib on top of the yoke intermediate the ends thereof, said rib being inclined on top, and a wedge driven between the under side of the rail base and the top of the rib.

8. A rail anchor comprising a resilient yoke extending transversely beneath the rail and having jaws at its ends engaging opposite sides of the rail base, a rib on top of the yoke intermediate the ends thereof, said rib being inclined on top, a wedge driven between the under side of the rail base and the top of the rib, and means for locking the wedge against sidewise displacement.

9. A rail anchor comprising a yoke extending transversely beneath the rail and having jaws at its ends engaging opposite sides of the rail base, an incline on top of the yoke intermediate the ends thereof, and a wedge driven between the under side of the rail base and the incline, the contiguous portions of the wedge and the incline having interlocking teeth for locking the wedge against withdrawal.

10. A rail anchor comprising a yoke extending transversely beneath the rail and having jaws at its ends engaging opposite sides of the rail base, a rib on top of the yoke intermediate the ends thereof, said rib being inclined on top, and a key between the yoke and the under side of the rail base, one side of the key abutting against one of the jaws of the yoke, and the other side having a wedge engageable with the top of the rib.

11. A rail anchor comprising a yoke extending transversely beneath the rail and having jaws at its ends engaging opposite sides of the rail base, a rib on top of the yoke

intermediate the ends thereof, said rib being inclined on top, and a key between the yoke and the under side of the rail base, one side of the key having a wedge engageable 5 with the top of the rib, and the other side of the key abutting against one of the jaws of the yoke, said jaw having a recess located below the plane of the under side of the rail base, in which recess the last mentioned side 10 of the key seats.

12. A rail anchor comprising a resilient yoke extending transversely of the rail and having jaws at its ends engaging opposite sides of the rail base, a rib on top of the yoke 15 intermediate the ends thereof, said rib being inclined on top, and a wedge driven between the under side of the rail base and the

top of the rib, said wedge and rib having interlocking parts.

13. A rail anchor extending transversely 20 beneath the rail and having jaws at its ends engaging opposite sides of the rail base, a rib on top of the yoke intermediate the ends thereof, said rib being inclined on top, and a wedge driven between the under side of the rail base and the top of the rib, said rib and 25 wedge having interlocking parts.

In testimony whereof I affix my signature in presence of two witnesses.

JOHN HERRON.
